UNITED STATES PATENT OFFICE.

WESLEY D. SNELL, OF ROCHESTER, NEW YORK.

CHURN-DASHER.

SPECIFICATION forming part of Letters Patent No. 225,655, dated March 16, 1880.

Application filed January 5, 1880.

To all whom it may concern:

Be it known that I, WESLEY D. SNELL, of Rochester, in the county of Monroe and State of New York, have invented certain new and 5 useful Improvements in Churn-Dashers; and I do hereby declare that the following is a full, clear, and exact description of the invention, which will enable others skilled in the art to which it appertains to make and use the same, 10 reference being had to the accompanying drawings, which form a part of this specification, and in which—

Figure 1 is a perspective view. Fig. 2 is a bottom view. Fig. 3 is a transverse vertical 15 section, and Fig. 4 is a partial longitudinal vertical section.

Similar letters of reference indicate corresponding parts in all the figures.

My invention has relation to that class of 20 reciprocating churn-dashers which are composed of two parallel leaves or blades hinged upon a reciprocating bar or cross-head; and it consists in the improved construction hereinafter described, and particularly pointed out 25 in the claim.

In the drawings, A is the dasher-staff, which is hinged in a bifurcated head, B, at its lower end. The head B is pivoted by a bolt, b, which is screwed into its under side upon the middle 30 of the cross-piece C, the bolt b passing vertically through said cross-piece, and having a cross-head or key, c, at its lower end, upon the under side of cross-piece C, against which it bears, said key being held in place by the nut d.

The cross-piece C is made with a longitudinal 35 rib or flange, e, on its under side, which is enlarged on the middle to conform to the shape of the central key, c, as will be seen more clearly by reference to Fig. 2 of the drawings. In 40 turning the hinged staff or handle A and its pivoted head B the key is turned with it.

D D are cross-heads, secured one at each end of the cross piece or bar C, and provided with stops f f. E E are the dasher wings or 45 blades, which are hung by their pivots g g g in the cross-heads D D, one on each side of bar C, against the under side of which the inner sides of the wings E E impinge, separated from each other by the downward-projecting 50 rib e. The middle part of the inner side of each of the wings is cut out to make room for

the central enlargement, e', of said rib or flange, and by turning the key c across or crosswise upon said enlargement e', as shown in Fig. 2 of the drawings, the wings or blades E E will 55 be locked in a horizontal position. By turning the key, by means of the staff A, in the opposite direction, as shown by dotted lines in said figure, the wings will be free to swing in a downward direction, as indicated 60 by the dotted lines in Fig. 3. When in this position the dasher-wings will bear against the shoulder of cross-bar C and their outer stops, f f, on the downward stroke of the dasher, but will be released on the upward 65 stroke, so as to cut the cream with ease; and when the butter has been made it is withdrawn from the churn by turning staff A (and with it the key c) one-fourth around, when the dasher is at the end of its downward stroke, 70 which locks the blades E E in their horizontal rigid position, so that the butter may be lifted up upon them, the buttermilk draining off through the perforations with which the blades are provided.

By hinging the staff A to its head B it may be held in a bent position while raising and carrying the dasher, thereby facilitating these operations.

I am aware that churn-dashers have been 80 constructed before with pivoted dash-leaves adapted to be held in a horizontal position by a turn-button, and I do not claim such construction, broadly; but

What I claim, and desire to secure by Let- 85 ters Patent of the United States, is—

The herein-described churn-dasher, consisting of the hinged or jointed staff A, pivoted head B, provided with the bolt b and key c, cross-bar C, cross-heads D D, having stops f 90 f, and pivoted parallel blades E E, arranged on opposite sides of the cross-bar C, the whole constructed and combined to operate substantially as and for the purpose herein shown and described.

In testimony that I claim the foregoing as my own I have hereto affixed my signature in presence of two witnesses.

WESLEY D. SNELL.
